UNITED STATES PATENT OFFICE.

LESSLEY W. MACK, OF VAN NORMAN, MONTANA.

GOLD-SEPARATING MACHINE.

Application filed May 6, 1925. Serial No. 28,429.

This invention relates to improvements in means for separating precious metals from other foreign materials.

The primary object of this invention is the provision of apparatus by means of which gold and other precious metals may be pneumatically segregated from other worthless materials mixed therewith.

Other objects and advantages of this invention will be apparent during the course of the following detailed description.

In the accompanying drawings, forming a part of this specification, and wherein similar reference characters designate corresponding parts throughout the several views,

Figure 1 is a plan view of the improved apparatus.

Figure 2 is a side elevation of the improved apparatus.

Figure 3 is a plan view of the housing of the apparatus with the cover removed, showing the novel path of travel of the materials from which the precious metal is to be reclaimed.

Figure 4 is a cross sectional view taken substantially on the line 4—4 of Figure 1.

Figure 5 is a fragmentary view, partly in section, showing that part of the apparatus by which the ore mass is fed into the improved device.

Figure 6 is a fragmentary bottom plan view of the gold receiving receptacle, with the lid open.

In the drawings, wherein for the purpose of illustration is shown only a preferred embodiment of the invention, the letter A may generally designate the improved apparatus, which may include the housing B, and ore feed means C.

Referring to the housing or casing B, the same preferably comprises the body portion 10; platform 11; and detachable closure 12. The platform 11 is preferably flat, and adapted to be supported upwardly of a ground or floor surface 13, as by means of substantially angle shaped supporting legs 15, which may be attached in any approved manner to the platform 11, so that the latter may be horizontally supported in spaced relation above the surface 13. This platform 11 is imperforate except for an opening 17, which is substantially circular, and through which the precious metal is adapted to pass after the same has been pneumatically sepa-

rated and segregated from the ore mass in the body 10, and through which opening 17 the gold or other precious metal falls into a receiving receptacle 18 to be subsequently described.

The body portion 10 is preferably formed of substantially parallel spaced walls to provide a channel or way through which the blast of air travels. The channel is closed at its lower portion by the platform 11, and at its upper portion by the detachable cover 12,

which is flat substantially the same as the platform 11. The body portion 10 preferably includes the substantially parallel inlet wall portions 20 and 21, having a way 22 therebetween, which is preferably straight, and slightly inclined at an acute angle to the vertical, substantially as is illustrated in Figure 2 of the drawings, in order to place the inlet way 22 in tangential relation to the spiral passageway 23 which is formed in the body 10. At the entrance to the way 23, the same is enlarged at 24, by recessing the walls 20 and 21 in concave manner, as is illustrated in Figures 2 and 3 of the drawings.

Contiguous with the wall 20 a downwardly convergent sloping spiral wall 25 is formed, which connects at 27 with the wall 21. From the juncture point 27 of the spiral sloping wall 25 with the end of the wall 21, a spiral tongue 30 is formed, in spiraling and sloping relation in the space within the spiral wall 25 above mentioned, and preferably parallel with the spiral wall 25; the tongue 30 preferably terminating at 31, with its edge tangentially arranged with the opening 17. The spiral wall or tongue 30 is thus so placed with respect to the wall 21 that the latter is tangential thereto. In this manner the sloping spiral walls 25 and 30 are in effect contiguous from the straight walls 20 and 21, so that the latter are tangential thereto. These spiral walls 25 and 30 provide a spiral way 23, which is of uniform height throughout its length, and of the same height as the inlet way 22. The inside surfaces 33 of the spiral walls 25 and 30 slope downwardly in convergent relation toward the base or platform 11, and the facing sloping surface 34 at the outer side of the wall 30 is preferably parallel with the surface 33, and therewith provides the spiral way 23 which is of uniform width throughout its length, as well as of uniform height,

The way 23 spirals from the entrance 22 towards the outlet opening 17.

The closure 12 is preferably flat, and is provided with laterally extending attaching ears 36, adapted for cooperation with lugs 37 provided at the exterior of the body wall 25, for receiving securing bolts or elements 38 by means of which to attach the closure or cover 12 to enclose the inlet and spiral ways 22 and 23 at the top thereof. This closure 12 is preferably provided with an opening 40 in the same, considerably larger than the opening 17, and in aligning relation with the opening 17. The opening 40 has the edges thereof beveled so that they slope in one direction; the opening 40 having the lower edge thereof preferably lying flush with the inner edge of the spiral wall or tongue 30, as is illustrated in Figure 4 of the drawings. The opening 40 has the edge thereof really inclined towards a horizontal duct or way 41, through which the refuse and worthless materials pass; the said duct 41 being formed by a substantially U-shaped member 42, which is adapted for bolting or attachment as at 43 upon the top member 12, and the inner end of which guide member 42 is closed, so that the materials passing through the opening 40 must of necessity travel along the duct 41 and be so conveyed to any desirable exit location.

The source of air has not been shown, but it is to be understood that the same may be a blower fan, or analogous means for producing the blast or pneumatic draft; it being understood that this blower or other means for producing the blast of air is connected at the edge 50 of the body 10, so that the air first travels into the body 10 through the enlarged portion 24 of the channel way 32.

The improved feed means C is preferably located upon the closure or top member 12 of the housing B, between the source of the air blast and the spiral channel 23.

The feeder construction C preferably is of the closed valve type, and the same includes a casing 55, which is bolted, as at 56, or otherwise secured upon the top member 12, and provides the substantially circular compartment 58 therein within which the feeding valve 60 is rotatably mounted. The casing 55 upwardly therein provides the inlet opening 61, and supports the hopper 62 thereover, into which the materials are fed. The top member 12 or closure of the body of the casing B is provided with a feed opening 66 therein, through which the materials are fed by means of the valve 60 into the channel or way 22 between the source of air blast and the spiral way 23. The valve or feed member 60 is preferably of cylindrical formation, rotatably supported upon a horizontal shaft 67 in the compartment 58 provided therefor. It is provided with a plu-

rality of radially extending pockets 70, which are narrow, although as deep as need be, and which are of such width that the same cannot be in communication with the openings 61 and 66 at the same time. The valve 60 snugly fits in the opening 58, to permit its rotation, but preventing the blast of air passing into the hopper 62.

Referring to the method which is carried out by functioning of the apparatus, A, the fan (not shown), is of course set in operation, to force a blast of air into the way 22, and around the spiral way 23 and upwardly through the opening 40 and through the exit duct 41. The mass of ore is force fed thru the hopper 62, by the valve 60, and in regulated quantities dropped from above into the blast of air passing along the way 22, and has an opportunity to be thoroughly distributed in the blast of air. The materials are then whirled along the way 22, and enter the spiral way 23. Incident to the sloping wall 33, the materials rolling therealong will have an opportunity to separate, incident to variance in specific gravities, and the heavier precious metal will roll downwardly over the sloping surface 33, and as end of the travel of the same along the spiral way terminates at the opening 17, the precious metals pass downwardly into the receptacle 18. On the other hand, the lighter particles, such as sand, gravel, dry dirt, and crushed stone incident to the well regulated blast of air, which is just sufficient to keep the same in suspension, will pass along the sloping wall 33, and after the same has traveled along the spiral way 23, the said worthless particles in suspension will be carried through the beveled opening 40, into the exit duct 41, and will pass to any suitable location.

The precious metal collector 18 is really in the form of a hollow frusto-conical receptacle, which at its upper restricted end 80 is secured as at 81 below the platform 11, and with the compartment 82 communicating with the opening 17. At its larger and exit end the receptacle 18 supports the disc-shaped closure 83, which is eccentrically pivoted as at 84, so that the same may be swung to close the compartment 82, or swung laterally to open the compartment 82, as is illustrated in Figure 6.

From the foregoing description of this invention it will be apparent that a novel apparatus has been provided for reclaiming gold from ore. It is to be particularly noted that the spiral channel is located in a horizontal plane, and the same is of uniform height and width throughout, with the walls sloping in converging relation to the vertical. In this manner the blast of air may be regulated, and the ore is uniformly treated, and does away with the eccentric eddies which would otherwise occur. The air cur-

rent takes place throughout the entire height of the spiral way, and incident to the uniformity of the spiral way, the blast of air continues at approximately the same velocity up to the point of final segregation of the precious metals from the other worthless materials.

Various changes in the shape, size, and arrangement of parts may be made to the form of invention herein shown and described, without departing from the spirit of the invention or the scope of the claims.

I claim:

1. In apparatus of the class described a housing having a spiral channel therein of substantially uniform width and height throughout the length thereof, said spiral channel having sloping walls and a precious metal exit opening at the convergent point 20 of the wall and an opposite worthless material exit opening, and means for feeding materials into the spiral channel.

2. In apparatus for pneumatically separating precious metals from other foreign materials the combination of a housing having a spiral way therethrough with an entrance opening at the edge of the spiral way and centrally disposed precious metal exit and worthless material exit openings at the 30 opposite ends of the spiral way, said spiral way having facing walls which slope at an incline to the vertical in convergent relation towards the precious metal exit opening.

3. In apparatus for pneumatically separating precious metals from other foreign materials the combination of a housing having a spiral way therethrough with an entrance opening at the edge of the spiral way and centrally disposed precious metal exit 40 and worthless material exit openings at the opposite end of the spiral way, said spiral way having a wall which slopes at an incline to the vertical in convergent relation towards the precious metal exit opening, and said spiral way being of uniform width and height throughout the length of the same.

4. In apparatus for pneumatically separating precious metals from other materials a housing having a spiral channel therein of uniform dimension throughout the length thereof, said spiral channel having a tangential inlet opening and centrally disposed precious metal and worthless material exit openings.

5. In apparatus for pneumatically separating precious metals from other materials a housing having a spiral channel therein of uniform dimensions throughout the length thereof, said spiral channel having a tangential inlet opening and centrally disposed precious metal and worthless material openings, said spiral channel having facing side wall surfaces sloping uniformly at an incline to the vertical towards the precious metal exit opening.

6. In apparatus of the class described a housing providing a spiral passageway of uniform dimension throughout the length thereof and having a tangential entrance channel to the spiral channel, means for feeding a blast of air into the entrance channel, means for downwardly feeding a quantity of mixed precious metals and other foreign materials into the blast of air traveling through the entrance channel, said housing at the central end of said spiral channel providing upper and lower openings for the respective exit of worthless and precious metals.

7. Apparatus of the class described comprising a supporting base having a precious metal exit opening therein, a top having a worthless metal exit opening therein larger than the first mentioned opening, and a body between the bottom and top including a pair 85 of spaced arcuated walls disposed in substantially parallel relation to provide a channel shaped spiral way into which a blast of air is adapted to be fed, said walls terminating so that the central end of the spiral way 90 terminates at the openings above mentioned, and means for feeding mixed precious metals and other materials into the inlet end of the spiral way.

8. Apparatus for the separating of materials comprising a housing having vertically sloping walls defining a horizontal passageway including a plurality of convolutions all of which are disposed in the same horizontal plane and of the same height in said horizontal plane, means for tangentially feeding a precious metal laden body of air tangentially into the outer end of the passageway, and means providing an upper worthless material exit opening at the center of the spiral 100 way and a lower precious metal exit opening at the lower end of the spiral way.

9. Apparatus of the class described comprising a housing including arcuated spaced walls arranged in the same horizontal plane, 110 the walls having spaced surfaces to provide a spiral way between the facing surfaces thereof including a plurality of convolutions all disposed in the same horizontal plane and of the same height in said horizontal plane, 115 the said surfaces of the walls which form the spiral way sloping downwardly to converge the spiral way from the upper end thereof downwardly so that the convolutions of the spiral way at the upper ends thereof are 120 greater in dimension from side to side than at the lower end thereof, the convolutions terminating at substantially the central axis defined by said spiral passageway to provide a substantially funnel-shaped compartment 125 at the central axis of said spiral passageway, means covering the upper end of said spiral passageway and having a central opening therein for the compartment as a means for exit of worthless materials which do not fall 130

downwardly over the sloping surfaces of the walls which provide the spiral way, base means on which the walls rest and closing the lower end of said spiral passageway and at the lower end of said central compartment providing a reduced exit opening smaller than the exit opening above men-

tioned for discharge of precious materials from the spiral passageway, and means for feeding a blast of air with precious metals ¹⁰ supported therein tangentially into the spiral passageway.

LESSLEY W. MACK.
